UNITED STATES PATENT OFFICE.

MARK W. DEWEY, OF SYRACUSE, NEW YORK, ASSIGNOR OF TWO-THIRDS
TO EMIL LAASS AND CHARLES H. DUELL, BOTH OF SAME PLACE.

ELECTRICAL TYPE-WRITER.

SPECIFICATION forming part of Letters Patent No. 406,390, dated July 2, 1889.

Application filed December 1, 1887. Renewed November 24, 1888. Serial No. 291,803. (No model.)

To all whom it may concern:

Be it known that I, MARK W. DEWEY, of Syracuse, in the county of Onondaga, in the State of New York, have invented new and 5 useful Improvements in Electric Type-Writers, of which the following, taken in connection with the accompanying drawings, is a full, clear, and exact description:

Although this type-writer may be operated 10 by most of the well-known means for operating electrical type-writers having type-wheels or a magnet for every character, yet it is more especially adapted to be operated by a selecting device in the vicinity of the instrument, similar to the one described in my prior 15 application, Serial No. 251,645, filed October 6, 1887, and operated at a distant point by either a few keys manipulated to form combinations or by a complete key-board.

20 The objects of my invention are to print a message at a receiving-station as fast as keys at the transmitting-station are depressed, using independently-movable type-bars without necessitating the employment of isochronously-moving wheels having the type affixed thereto, or without the necessity of waiting for mechanism to register accurately before printing; and the object is also to print the 25 message type-writer style on a letter-sheet, and to provide means of placing the carriage 30 in any position and turning the platen with more ease and greater speed than on ordinary type-writers.

In the annexed drawings, Figure 1 is a side 35 elevation of the selecting device. Fig. 2 is a plan view of the magnets and contact-points of the selecting device. Fig. 3 is an elevation of the printer, taken in a plane on the line $x-x$, Fig. 4; Fig. 4, a plan view of the printer 40 without the carriage, showing the arrangement of the circuits. Fig. 5 is a plan view of the carriage and platen. Fig. 6 shows the means for moving the carriage against the tension of the spring to make space between 45 letters to be printed or space between words. Fig. 7 shows face view of the arrangement of magnets for shifting the type-carrier. Fig. 8 is a plan view of the two different key-boards and their connection with the battery and 50 indicator. Fig. 9 is a side elevation of keys. Fig. 10 is a side elevation of the indicator.

Fig. 11 is a detached plan view of the switch-bar for turning the platen to a new line or making space between messages written on same sheet. Fig. 12 is a plan view of a portion of the screw for moving the platen. Fig. 13 is a side elevation of a modification of the circuit-maker of the local circuit controlling the feelers of the selecting device. Fig. 14 is a face view of the same. Fig. 15 55 is an enlarged view of Fig. 3. Fig. 16 is a front elevation of the selecting device; and Fig. 17 is an enlarged plan view of the printer, taken below the carriage, and illustrating the action of the shifting-lever for 60 turning the type-bar carrier so as to allow different type-bars to be operated by one and the same lever.

The selecting device illustrated in Fig. 1 of the drawings consists of five plates $p p$, pivoted in a suspended position and having their lower ends in proximity to and extending across the top of a series of feelers $A A$, which are pivoted to suitable supports B at one end, and are supported in a horizontal position by a prop B' at the opposite end. Each of said feelers is provided in its top edge with a number of notches $a a$, corresponding to the number of plates $p p$, the notches in each feeler being arranged in different relative position, 70 and in such position in relation to the plates $p p$ that by shifting one of said plates from its normal position only one of the feelers A will have all of its notches in coincidence with all the plates $p p$. Each of the plates p 75 p is held in its normal position by a spring b holding plate to rest against a stop b' . To the upper part of each of said plates is attached an armature p' , and facing said armature is arranged a magnet m . From each of the magnets m is extended a wire c , which 80 terminates under the key-board C , or is connected with a metal bar c' , arranged under the said key-board. The keys of the key-board are composed of metal, and are supported isolated from the aforesaid metallic bar by suitable springs c'' , as illustrated in Fig. 9 of the drawings, and are pivoted to a metal bar d , which is connected with the main battery D . The aforesaid key-board 85 may either consist of a complete set of keys, one for each letter and punctuation-marks, 90 or may consist of a set of keys for each letter and punctuation-marks, 95 or may consist of a set of keys for each letter and punctuation-marks, 100

and for shifting the carriage and for spacing, or consist of a limited number of keys equal to the number of plates p p heretofore referred to, said second form of key-board being represented at C' in Fig. 8 of the drawings.

To the top of each feeler A is secured an armature d' , and over the armatures of the entire set of feelers is arranged a series of electro-magnets m' , which are connected with a local battery D' , with which latter are also connected the pivots of the plates p p by wires e . The plates p p and their pivots, being composed of metal, form electric conductors of said plates.

In front of each plate p , at one end of the base thereof, is arranged a stationary stop f , (see Fig. 16 of the drawings,) which comes in contact with the plate when actuated by the armature p' on the upper end thereof, being attracted by the magnet m . At the side of the stops f are oscillatory metallic arms f' , which are secured to a horizontal bar f'' , journaled in suitable insulated bearings g g .

The arms f' f' are held normally out of contact with the stops f by a spring or springs g' , crowding the said arms into the aforesaid position. The bar f'' is connected with the magnets m' by wire e' , and from said bar projects another arm carrying an armature g'' , which faces an electro-magnet g''' , and a wire c'' connects said magnet with each of the magnets m m m m , and another wire e''' leads from the magnet g''' to a magnet g'''' , which, by its attraction of the armature on the bell-hammer h , sounds the gong h' . A wire c'''' is extended from the magnet g'''' to ground.

At the receiving-station I arrange the following electro-magnetic type-writer: On a vertical pivot i , I pivot the annular type-bar carrier G , on which are pivoted the bars or arms j , to the free end of which the types are affixed. Radially around the exterior of the carrier G is a series of levers k k , pivoted on posts J' , the upper ends of which project horizontally across the tops of the levers at the end most remote from the carrier G , and set-screws k'' are extended vertically through the horizontal projections of the posts, to serve as adjustable stops, against which the aforesaid ends of the levers normally rest. To the under side of the said end of each lever is attached an armature k''' , under which is arranged a magnet m'' . There is one lever k for each three adjacent type-bars j , as best seen in Figs. 4 and 17 of the drawings, and each of said type-bars has pivoted to it a cam l , adapted to bear on top of a suitable bearing on the adjacent end of the lever k , so that when the armature k''' on the opposite end of the lever is attracted by the magnet m'' the resultant upward movement of the end of the lever under the cam l will throw the free end of the type-bar up and cause the type to make the impression on the paper supported on the platen F . On arms l' , projecting from the supporting-frame E of the type-writer, is

pivoted the feed-screw H , which moves the carriage I and platen F , mounted thereon. The screw is rotated by means of a ratchet-wheel l'' , attached to the end of the screw, and a lever n , pivoted on the frame E and having connected to it a pawl l''' , engaging the ratchet-wheel l'' , as shown in Fig. 6 of the drawings. An armature n' on the lever n faces a magnet m''' , which when energized attracts the armature, and thus draws the lever n from the ratchet-wheel l'' , and a subsequent break of the circuit with which the magnet is connected releases the armature and lever n and allows a spring n'' to draw the lever toward the ratchet-wheel l'' , and thereby cause the pawl l''' to partly turn said wheel and screw H .

On the carriage is pivoted a two-armed lever o , one arm of which projects across the top of the screw H , and has affixed to it a downward-projecting pin o''' , which enters into the groove of the screw. The other arm of the lever o projects rearward below the screw, and against the under side of said arm bears the end of one of the arms of a pivoted bell-crank lever o' , the end of the other arm of which has affixed to it an armature o'' , opposite which is a magnet m'''' . The attraction of the armature by the magnet causes the lever o' to press upward the lever o , and thereby throw the pin o''' out of engagement with the screw H , and thus release the carriage I from the action of the screw. The carriage, when moved by the screw, moves under the resistance of a spring-arm K , which is connected with the carriage, and when the lever o is lifted to raise the pin o''' out of engagement with the screw, as hereinbefore described, the said spring-arm automatically carries back the carriage I . On the end of the platen F is secured the ratchet-wheel L , and on a post L' , rising from the carriage, is pivoted a lever L'' , to one end of which is connected a pawl q , which engages the ratchet-wheel and partly turns the same when the said end of the lever is raised. (See Fig. 15 of the drawings.) A dog q' , pivoted on the post L' and engaging the ratchet-wheel, prevents the retrograde movement thereof. The free end of the lever L'' projects rearward, for the purpose hereinafter explained. To the end of the frame E from which the carriage starts is secured a hook-arm J , which projects from the frame parallel with the line of travel of the carriage, and has an upward-projecting hook with an inclined face on its under side. In the retreat of the carriage under the influence of the spring-arm K , hereinbefore described, the free end of the lever L'' passes under the inclined face of the hook on the arm J , and is thereby depressed. The depression of said lever causes the pawl q to partly turn the ratchet-wheel L , and with it the platen F , thereby obtaining the requisite spacings between the lines imprinted on the paper.

As hereinbefore stated, there is one lever k for each three adjacent type-bars j , and in order to adapt said lever to operate either of

said type-bars separately from the other I employ the following devices: On a metallic post M is pivoted horizontally a metallic lever K', one end of which is coupled to type-bar carrier G, and the opposite end projects between two magnets M' M'', as shown in Fig. 7 of the drawings. A spring-arm s projects from the post M and has its opposite end connected to the lever K', so as to hold the same centrally 10 between the magnets M' M''. At opposite sides of the lever K' are contact-points u, supported on a post u', and a metal plate u'' connects the post u' with a binding-screw N. A wire t is extended from the device to magnet 15 m'' and from said magnet to post M by wire v, as shown in Figs. 3 and 4 of the drawings. A wire v'' connects the binding-screw N with a battery D'', with which is also connected, by a wire v', the metallic pivotal support B of 20 the feelers A A. From the lever K' is suspended an armature w, which faces a magnet M''', and has its lower extremity arranged to come in contact with a set-screw x when the armature is attracted by the magnet 25 25, said set-screw being connected to metallic lug mounted on the metal plate u'', hereinbefore referred to. Over the free ends of each set of three feelers A are arranged two contact-points h, from one of which one of the 30 wires y y' y'' is extended, said wires being connected to the magnets M' M'' M'''.

The result is that when one of the feelers rises and comes in contact with the contact-point h an electric impulse passes from the battery D'' through the feeler A, thence 35 through one of the wires y y' y'', to the magnets M' M'' M'''. The circuit through the other contact-point of the feeler remains open until connection is made through one of the 40 contact-points u or w by the movement of lever K. The impulse through the magnets M' M'' causes the lever K' to be drawn to one side or the other, and by this movement said lever turns the type-bar carrier G so as 45 to bring the requisite type-bar j under the lever K. The lever K' or its suspended contact-point w, coming in contact with one of the points u or set-screw x, causes the current to pass through the second contact-point 50 of the feeler through the wire leading to magnet m'', attracting the armature of the required printing-lever then on return through magnet m''', moving carriage for next letter then to post M and stops u and post u', to the 55 plate u'' and binding-screw N, and thence to battery D''. The resistance in the first circuit causes the greater part of the current to flow through the second circuit when closed. The second current passes, by means of wires 60 t v, through the magnet m'', which latter attracts the lever k and thereby causes the type-bar j to imprint the paper on the platen F. One of the contact-points h, over one feeler A, is connected by wire t' t'' with the 65 magnet m''', and thus, when said feeler comes in contact with the aforesaid point, the said magnet is energized and caused to actu-

ate the bell-crank lever o', so as to lift the arm o and thereby release the carriage from its engagement with the feed-screw H. The 70 said carriage is then carried back to its original position by the spring-arm K.

P represents an indicator, showing at the transmitting-station the position of the type-writer carriage I at the receiving-station, said 75 indicator consisting of two disks 1 2, of the same diameter, pivoted to one and the same shaft and closely one over the other, and each provided with ratchet-teeth on its periphery, one disk having connected to it one end of a 80 coil-spring, which imparts rotary motion to said disk, and a spiral spring a' connects the two disks with each other. A pawl a'' is connected to an armature A', which is pivoted in such a position that by its oscillation it carries the pawl alternately from the ratchet of one disk to that of the other disk, and in this manner allow the disk to turn intermittently under the influence of its spring. The magnet U, which actuates the armature a', is 85 connected with the wire leading from the keyboard C to the battery D, and thus each movement of one of the keys causes the indicator P to move the distance of one of the notches in one of the ratchets. At the intermediate 90 station of the line I may employ, in connection with the plates p and their magnets m of the selecting device, a circuit maker and breaker consisting of a short lever T, pivoted on the plate p and extending toward the upper end of the plate, where said lever is provided with prongs or wires T', which project through orifices O O in the armature of the plate p, as shown in Figs. 13 and 14 of the drawings. The pivoted end of the lever T is 95 provided with a heel V, which, when the plate is attracted by the magnet m, comes in contact with a binding-screw V', to which is connected the wire e, leading to the battery D', as shown in Fig. 1 of the drawings.

The lower end of the plate p, coming at the same time in contact with a point R, from which a wire R' leads to the magnet m', which is also connected with the battery D', causes the feeler A to be lifted.

In breaking the circuit through the magnet m by the release of the key of the key-board C or C', the lever T becomes released from the magnet m, and thus breaks the circuit through the plate p independent of said plate.

The operation of my invention, briefly stated, is as follows: Assuming the key-board C' with only five keys is employed, the operator depresses either one or more keys simultaneously, according to the letter or character to be transmitted. The depression of said key or keys closes the circuit over one or more wires c and energizes a corresponding number of magnets m, which attract the plate or plates p, the lower end of the latter 125 coming in contact with the stop f. The circuit which passes through the magnet m also passes through the magnet g'', which attracts the arm f' and throws the same also 130

into contact with the stop *f*. This closes the local circuit of battery *D'*, which energizes the magnets *m'* and causes the same to attract the feelers *A A*. However, only that 5 one of said feelers which has all of its notches coinciding with the lower edges of all the plates *p p* is allowed to rise, the other feelers, having their notches in different position, being prevented from rising by the collision of 10 said feelers with the plates *p*. The elevated feeler closes the local circuit of battery *D''* first by the contact of the feeler with one of the contact-points *h*, and thereby one of the shifting-magnets *M' M'' M'''* is energized, 15 so as to hold the lever *K'* either in a central position or throw it to one side or the other, and thereby turns the type-bar carrier *G* so as to bring the proper type-lever in position for the printing-lever *k* to operate on it. By 20 energizing one of the aforesaid magnets the circuit is completed through one of the printing-magnets *m''*, either by the contact of the lever *K'* with one of the stops *u* or by the contact of the suspended armature *w* with the 25 stop *x*, which allows the current to flow also through the second contact-point *h* of the feeler. In the return-wire of the last-mentioned circuit is the magnet *m'''*, which moves the platen of the type-writer to produce the 30 requisite spacing between letters.

Having described my invention, what I claim as new, and desire to secure by Letters Patent, is—

1. In combination with the feelers *A A* and 35 the plates *p p*, provided with armatures *p' p'*, separate magnets for the respective plates and transmitting-keys electrically connected with the aforesaid magnets, as set forth.

2. In combination with circuit making and 40 breaking keys at the transmitting-station, the feelers *A A* and the plates *p p* at the receiving-station, separate magnets *m m* for the respective plates, main-line wires *c c c*, connecting the keys with the magnets, circuit 45 making and breaking points arranged to come in contact with the feelers by the movement of the latter, and printing-levers operated by magnets electrically connected with the aforesaid circuit making and breaking 50 points, substantially as set forth.

3. In combination with circuit making and 55 breaking keys at the transmitting-station, the feelers *A A* and plates *p p* at the receiving-station, separate magnets *m m* for the respective plates, main-line wires *c c c*, connecting the keys with said magnets, circuit making and breaking points *h h*, arranged to come in contact with the feelers by the movement of the latter, a type-writer at the 60 receiving-station, a platen-carriage on said type-writer, feed mechanism for moving said

carriage, the lever *o'*, adapted to throw the feed mechanism in and out of gear, an armature on said lever, a magnet *m'''* for operating said lever, and wires connecting magnets 65 *m'''* with one of the contact-points *h*, substantially as and for the purpose set forth.

4. In combination with the platen *F*, the pivoted carrier *G*, type-bars *j j j*, pivoted to and arranged in sets on said carrier, the series of levers *k k k*, arranged one for each set of type-bars, electro-magnets *m'' m'' m''* for operating said levers, the lever *K'* for turning the carrier, and electro-magnets *M' M''*, for operating the lever *K'*, substantially 75 as described and shown.

5. In combination with the frame *E*, carriage *I*, and platen *F*, the screw *H*, pivoted to the said frame, the ratchet-wheel *l''*, attached to said screw, lever *n*, and pawl *l'''* for 80 turning the screw, and an arm *o*, pivoted to the carriage and adapted to engage and release the screw, substantially as and for the purpose set forth.

6. In combination with the frame *E*, carriage *I*, and platen *F*, the screw *H*, pivoted to the said frame, the ratchet-wheel *l''*, secured to the screw, the pivoted lever *n*, provided with the armature *n'*, the pawl *l'''*, connected to said lever and engaging the ratchet-wheel, 90 the electro-magnet *m'''*, facing the said armature, and a circuit maker and breaker in the circuit with which said magnet is connected, as set forth.

7. In combination with the frame *E*, carriage *I*, and platen *F*, the screw *H*, pivoted to said frame, the ratchet-wheel *l''*, lever *n*, and pawl *l'''* for turning the screw, the arm *o*, pivoted to the carriage and adapted to engage and release the screw, and the lever *o'*, 100 adapted to throw the arm *o* out of engagement with the screw, substantially as described and shown.

8. In combination with the frame *E*, carriage *I*, and platen *F*, the screw *H*, pivoted to 105 said frame, the ratchet-wheel *l''*, lever *n*, and pawl *l'''* for turning the screw, the arm *o*, pivoted to the carriage and adapted to engage and release the screw, the lever *o'*, adapted to throw the arm *o* out of engagement with the 110 screw, and the spring-lever *K*, connected with the carriage to retrograde the same when released from the screw, as set forth.

In testimony whereof I have hereunto signed my name, in the presence of two witnesses, at 115 Syracuse, in the county of Onondaga, in the State of New York, this 30th day of November, 1887.

MARK W. DEWEY. [L. S.]
